UNITED STATES PATENT OFFICE.

HORATIO N. HERRIMAN, OF CLEVELAND, OHIO.

HATCH-COVER FASTENER.

1,008,146.

Specification of Letters Patent. Patented Nov. 7, 1911.

Application filed March 16, 1911. Serial No. 614,797.

To all whom it may concern:

Be it known that I, HORATIO N. HERRIMAN, a citizen of the United States, resident of Cleveland, county of Cuyahoga, and State of Ohio, have invented a new and useful improvement in Hatch-Cover Fasteners, of which the following is a specification, the principle of the invention being herein explained and the best mode in which I have contemplated applying that principle, so as to distinguish it from other inventions.

My invention relates to devices for fastening down hatch-covers of vessels, its object being to provide a device of this character which will be economical in its construction and simple and efficient in its operation.

The said invention consists of means hereinafter fully described and particularly set forth in the claims.

The annexed drawing and the following description set forth in detail certain means embodying my invention, the disclosed means, however, constituting but one of various mechanical forms in which the principle of the invention may be used.

In said annexed drawing:—Figure 1 is a vertical axial section of a device embodying my invention, together with a fragmentary section of the hatchway of a vessel and cover therefor. Fig. 2 is a plan of the device, and plan of a fragmentary portion of the hatchway and cover. Fig. 3 is a section taken upon the plane indicated by line III—III of Fig. 1.

The combing A has secured thereto by means of suitable rivets and projecting horizontally therefrom, a bracket B, Fig. 1, which is formed with a slot having a vertical portion b and a horizontal portion b'. Seated in this slot is a horizontal pivotal pin C' which forms the pivotal axis of a contractile and expansible fastening member C, slotted to receive the said bracket. The said member C consists of three parts, namely, an L-shaped pivotal part C², a vertically sliding part C³, and a contracting bolt C⁴. The outer or normally vertical portion c of the member C² is provided with a longitudinal threaded bore c' which receives the bolt C⁴. This portion c is furthermore provided with a groove c², Fig. 3, parallel with the bore c', into which projects a tongue c³ formed in the sliding member C³. A cylindrical recess c⁴ formed in member C³ is adapted to receive the portion c of the

pivotal part C². The parts C³ and C² may slide with reference to each other, but rotation of the one with reference to the other is prevented by means of the tongue and groove.

Forming an integral part of the member C³ is the inwardly projecting portion C⁵ which is adapted to project over the hatchway and cover, as is shown. The outer portion of the member C³ is furthermore provided with an aperture c⁵ through which the bolt C⁴ projects, the head of the latter resting upon the outside of this member.

The part C² is provided with a seat c⁶ for the batten strip H and plate H', and is horizontal when the device is in its fastening position. Above this seat and fixed to the combing is a horizontal angle bar G forming an abutment for the batten strip H. The outer end of the bracket B is formed with an upwardly projecting lug b² which prevents the horizontal displacement of the batten plate H' when the device is in its non-operative position and the strip is lying loosely in the bracket, as shown in dotted lines in Fig. 1.

When the device is in its operative position, the part C² is placed so that the pivotal pin C' is in the vertical portion of the slot b, and the batten strip H and batten plate H' are placed intermediately of the seat c⁶ and the angle iron G, with the tarpaulin E in position between the strip H and angle G, and also between the hatch cover and inwardly projecting portion C⁵ of the part C³, as shown. By now screwing down the bolt C⁴, it will be seen that the part C³ will clamp down the cover, and the part C² secure the batten strip, batten plate and tarpaulin, between it and the angle G. To release the device, the bolt is unscrewed, whereupon the pin C' drops down into the horizontal portion of the slot b. This permits the member C to be drawn outwardly so as to permit its upper end to swing downwardly, allowing the inwardly projecting portion C⁵ to swing out of contact with the hatch cover, as will be readily understood.

Having fully described my invention, what I claim and desire to secure by Letters Patent is:—

1. In a hatch-cover fastener, the combination with an expansible and contractile fastening member pivotally mounted upon the hatch combing and adapted to project over the hatchway; of an abutment fixed to the

said combing and projecting therefrom above the pivotal axis of said member; said member and abutment forming a seat for the batten.

5 2. In a hatch-cover fastener, the combination with a fastening member comprising an element pivotally mounted upon the hatch combing, a second element slidably mounted on said first named element and adapted to 10 project over the hatch opening, and means adapted to draw said two elements toward each other; of an abutment fixed to said combing and projecting therefrom above the pivotal axis of said member; said pivotal element and abutment forming a seat for the batten.

15 3. In a hatch-cover fastener, the combination of an expansible and contractible fastening member; a bracket fixed to and projecting from the combing, and provided with a horizontally elongated slot, said fastening member being pivotally mounted in

25 said slot, and being furthermore adapted to project over the hatchway; and an abutment fixed to the combing and projecting therefrom above said bracket; the latter and abutment forming a seat for the batten.

4. In a hatch-cover fastener, the combination of an expansible and contractible fastening member; a bracket fixed to and projecting horizontally from the combing and provided with a horizontally and vertically elongated slot, said fastening member being pivotally mounted in the latter, and being furthermore adapted to project over the 30 hatchway; said bracket and abutment forming a seat for the batten.

35 Signed by me, this 24th day of February, 1911.

HORATIO N. HERRIMAN.
